UNITED STATES PATENT OFFICE.

SAMUEL S. HARPER, OF PHILADELPHIA, PENNSYLVANIA, ASSIGNOR TO THE HARPER RAILWAY TIE COMPANY, A CORPORATION OF SOUTH DAKOTA.

RAILROAD-TIE.

No. 869,178.

Specification of Letters Patent.

Patented Oct. 22, 1907.

Application filed December 22, 1903. Serial No. 186,147. Renewed March 16, 1907. Serial No. 362,729.

To all whom it may concern:-

Be it known that I, SAMUEL S. HARPER, a citizen of the United States, residing in the city of Philadelphia, county of Philadelphia and State of Pennsylvania; have 5 invented a certain new and useful Improvement in Railroad-Ties, of which the following is a description.

The present invention relates to improvements in railway ties formed of concrete or cement molded about an internal metallic core.

10 The objects of the invention are to reduce the cost of manufacture, to reduce the weight of the tie, and to render it easily and readily applied in use. The first of these objects is secured by reducing the amount of metal within the tie to the smallest possible amount. 15 The metal core is hollow, and preferably in the shape of a cylinder, of comparatively large diameter. In order to reduce the weight the concrete or cement within the cylindrical metal portion is cored out, except that portion immediately below the rails. This 20 portion of the tie is solid, as it must bear all of the weight of rails and traffic. In order to render the tie easily placed in position, the metal plates upon which the rails rest are provided with integral ears, which may be bent over the flange of the rail by an ordinary 25 spike maul, so as to hold the rail in position without the need of bolts, or other separable attaching media.

In order to better understand the nature of the invention, attention is directed to the accompanying drawings, which illustrate one embodiment of the invention, and in which

Figure 1 represents a longitudinal sectional view of the tie taken on the lines 1—1 of Fig. 2; Fig. 2 represents a transverse sectional view of the tie taken on the lines 2—2 of Fig. 1; Fig. 3 represents a side view of the internal core; and Fig. 4 represents a perspective view of the rail attaching clip.

In all of the several views like parts are designated by the same numerals of reference.

40 The concrete or cement portion 1 of the tie is molded in the usual shape about the core 2. The core is of thin metal, preferably cylindrical in shape, of comparatively large diameter, and is provided with a great many lips 3, which may be integral, and struck up out of the metal and bent, as shown. These lips are for the 45 purpose of serving as a support for the cement, and may be all of the same size, but they are preferably made as shown in Fig. 2, those which are opposite the corners of the tie being longer than the others, so that the corners will be more effectively supported. The tie is preferably cored out at 4 except the portions 5, 5 immediately below the rails. The rails are secured in place by means of the clips 6, which are made of heavy sheet metal, and have ears, 7, 8, which engage with the rail and may be bent over the flanges to hold it in place.

The ears may be bent on the flange of the rail by hammering, as by a spike maul. As shown in the drawings, the clips are provided with three ears 7, to engage with the inside of the rail, and with but two ears 8 on the outside. The strain upon the inside is in vertical direction, and for this reason three ears are used on this portion of the clip. 55

In order to add to the strength of the structure the ears 7 upon the inside or the ears 8 on the outside, or both, of the clip may be corrugated as shown at 9. On the outside of the clip a reverse or depending ear 10 65 may be arranged which will be embedded within the cement. The depending ear is for the purpose of resisting horizontal movement of the clip. The rail may be removed by bending the ears and releasing them from engagement with the rail flange by means of a 70 crowbar or other tool. Each of the clips 6 is secured in place by being provided with securing members, as two bands 11 which pass around the sides of the tie and are interlocked at 12. The clips rest within depressions 13 within the top of the tie, and the two bands may be 75 embedded within the tie a short distance, although this is not necessary. If for any reason it becomes necessary to tighten the bands, a shim may be driven between one of them and the tie, and if the clip becomes loose, or depressed within the top of the tie so 80 that the rail becomes out of alinement, a shim may be driven between the clip and the tie.

I prefer to mold the clip in place upon the tie, but this is not essential as the clip may be applied afterwards. In order to secure the hollow center of the tie 85 with the solid portion on each side thereof, it may be molded in sections, with one of the solid portions afterwards introduced in the form of a plug.

It will be noticed that there is no break in the upper surface or sides of the tie as would be the case if the 90 rail were attached by means which passes through the tie. For this reason it is impossible for water to pass into the tie and cause destructive effects, as by freezing, or corrosion.

As before described, the core 2 is hollow, and of comparatively large diameter. By the term "large diameter", I desire it understood that I mean a construction wherein the cement will be cored out, and still leave a considerable thickness of cement within the core, without requiring that the central opening be so small 95 as to cause no appreciable diminution of the weight of the tie. Any form of concrete or cement may be used, but I prefer to use it in such form that it may be readily molded about the central member. 100

It will be noticed that the rail securing clip is attached to that part of the tie which is solid. The solid portion will, therefore, be under the rail and the rail will be supported by the strongest portion of the tie. 105

The two bands 11 which pass around the side of the tie and secure the clip in place also constitute a means for strengthening the tie. The clip being attached to the point of greatest strength of the tie will also additionally reinforce it at the point at which it is subjected to the greatest strain. It will thus be seen that the tie is doubly reinforced at the points adjacent to the rail, first by the central plugs or solid portions of the tie, and second, by the clips and their securing bands which

5 surround the outside of the tie.

Having now described my invention, what I claim as new and desire to secure by Letters Patent, is:

1. A railway tie formed of concrete, with an internal hollow metallic strengthening member, the concrete within the strengthening member being cored out through part of the length of the tie a portion not being cored out.
2. A railway tie formed of concrete, with an internal hollow metallic strengthening member, the concrete within the strengthening member being cored out through part of the length of the tie, and solid below the rails.
3. A railway tie formed of concrete, with a rail securing clip, the said clip being formed of sheet metal and having integral ears, the said ears being capable of being bent over the flanges of the rail and into contact therewith, and constitute the holding means for the rail.
4. A railway tie formed of concrete, with a rail-securing clip, the said clip having securing members which pass around the tie.
5. A railway tie formed of concrete, with a rail-securing clip, the said clip having integral ears for attachment of the rail, and securing members, which pass around the tie.
6. A railway tie formed of concrete, with an internal hollow metallic member, the said member being of comparatively large size.
- 35 7. A railway tie formed of concrete, with an internal hollow metallic strengthening member and a rail-securing clip, the said clip having securing members which pass around the tie.
8. A railway tie formed of concrete, with an internal hollow metallic member, the said member having lips, for attachment of the concrete.
- 40 9. A railway tie formed of concrete, with an internal hollow metallic member, the said member having lips, for

attachment of the concrete, the lips adjacent to the corners of the tie being larger than those adjacent to the side.

10. A railway tie formed of concrete, with a rail-securing clip, the said clip having securing members, and a depending ear, which is embedded within the concrete, the said ear being parallel to the rail.

11. A railway tie formed of concrete, with a rail-securing clip, the said clip having securing members for the rail, bands, which surround the tie, on one side of the clip, and a depending ear on the other side, said ear being inserted within the concrete.

12. A railway tie having a rail securing clip, the said clip having integral rail securing ears, which are corrugated and capable of being bent over the flange of the rail and into contact therewith, the said ears constituting the securing means for the rail.

13. A railway tie formed of concrete with a rail securing clip, the said clip having securing members for the rail, and a securing band surrounding the tie.

14. A railway tie formed of concrete with a rail securing clip, the said clip having securing members for the rail, and a securing band surrounding the tie, the band being formed integrally with the clip.

15. A railway tie formed of concrete with a rail securing clip, the said clip having securing members, and a securing band which surrounds the tie and is embedded therein.

16. A railway tie formed of concrete with a rail securing clip, the said clip having securing members and a securing band which surrounds the tie and is embedded therein the band being integral with the clip.

17. A railway tie formed of concrete, with a rail securing clip, the said tie being hollow for a portion of its length and solid adjacent to the clip, the said clip having a securing band surrounding the tie coincident to the solid portion.

18. A railway tie formed of concrete with a rail securing clip, the said tie being hollow for a portion of its length and solid adjacent to the clip, the said clip having securing members for the rail and a securing band surrounding the tie coincident to the solid portion.

This specification signed and witnessed this 21st day of December 1903.

SAMUEL S. HARPER.
